COMBINED WINDOW GUARD AND SCREEN

Filed Aug. 8, 1932

UNITED STATES PATENT OFFICE

JOSEPH P. CONDON, OF OMAHA, NEBRASKA

COMBINED WINDOW GUARD AND SCREEN

Application filed August 8, 1932. Serial No. 627,849.

This invention relates to a combined window guard and screen for use on windows of residences and public buildings, and has for its object, broadly, to provide an appliance 5 for a window which will prevent ingress or egress therethrough of unauthorized persons or insects, said appliance to be of such construction that it will not obstruct ventilation or daylight and may be conveniently manufactured at a limited expense.

It is an object of the invention to provide a foraminous barrier or obstruction in the form of a combined grid and screen which may be inserted and locked in a window 15 frame, may be readily removed by the owner whenever desired, and will require no changes and will cause no injury to the window frame or woodwork of a building for installation.

20 The invention includes such a construction that it will not interfere with or prevent the use of storm window sash or other attachments for a window frame, but controls the sliding movement of the upper sash and permits a free sliding movement of the lower sash so that, while permitting ventilation, the device will protect against entrance of 25 burglars to residences, store buildings, and will prevent egress from hospitals or sanitaria.

With the foregoing objects in view the invention presents a new and useful construction, combination and arrangement of parts as described herein and claimed, and as illustrated in the accompanying drawing, it being understood that changes may be made in form, size, proportion of parts and minor details, said changes being within the scope 35 of the invention as claimed.

40 In the drawing, Fig. 1 is a side view of a combined window-guard and screen embodying the invention, parts being broken away.

Fig. 2 is an enlarged sectional detail showing the lower part of a window frame and 45 window sash together with the grid, the section being on line 2-2 of Fig. 3.

Fig. 3 is the view of the inner side of a window frame provided with the grid. Fig. 4 is an end view of the grid frame showing a 50 stationary locking-bar. Fig. 5 is an end

view of the grid frame showing a pivotally mounted locking-bar. Fig. 6 is an enlarged detail view of parts in transverse section on line 6-6 of Fig. 3.

Referring now to the drawing for a more 55 particular description, the invention is shown and described in connection with certain parts of a window frame 7, such as the vertical parting-strips 8 providing a pair of outer vertical channels 9 for receiving an upper window sash 10, and providing a pair 60 of inner vertical channels 11 for receiving a lower sash 12.

In order that the objects of the invention 65 may be attained as first mentioned I provide a grid 13 provided with a frame 14, said frame preferably being of rectangular form and constructed of channel iron to facilitate manufacture. However, I do not wish to be understood as limiting myself to the form or kind of material used in construction of any 70 of the parts of the grid.

Numerical 15 indicates a stationary locking-bar which is secured to one end of the grid-frame upon the front thereof, said bar having 75 an adequate width so that it will project outwardly beyond the end of said frame.

Numerical 16 indicates a second locking-bar which is mounted on the front side of the grid-frame on the end thereof opposite to 80 the bar 15, the mounting of this bar being such that it may have swinging movements, a pivot 17 being shown for said mounting.

The locking-bar 15 is provided with projections 18 and 18' at its ends to operate as 85 buffer-members, and as thus described it will be noted that the grid may be readily placed in its normal position in the window frame as shown in the drawing with its locking-bar 15 engaging in the outer channel 9 below the upper window sash 10, said locking-bar preventing an outward movement of said grid; also it will be noted that the projection or buffer element 18 at the lower end of the locking-bar 15 will engage 95 a parting-strip 8 to prevent an inward movement of the grid. The projection 18' at the upper end of the locking-bar 15 operates as a stop. It permits the upper window sash 100 to be moved downwardly a short distance

for any desired purpose, as for ventilation, but limits the distance of said downward movement.

The locking-bar 16 has an adequate width 5 so that, when swung downwardly to a vertical position it may enter a channel 9 to prevent an outward movement of the grid. This locking-bar, at its lower end, is provided with a projection or buffer-element 10 19, and when said bar has been swung downwardly, as mentioned, this projection may engage a parting-strip 8 to prevent a movement of the grid inwardly of the window frame.

15 In operation, to secure the grid in locked position, the locking-bar 16 is first swung to inoperative position as indicated by broken lines in Fig. 1 of the drawing. The grid is then fitted into the outer part of the window frame 7 as best shown in Fig. 6, the stationary locking-bar 15 engaging in the channel 9 with its projection 18 engaging the parting-strip 8. The locking-bar 16 may then be swung to operative position into a 25 channel 9 with its projection 19 engaging a parting-strip 8.

It will be seen that an unauthorized person at the outside of a building may be prevented from gaining entrance by operation 30 of the grid. The lower window sash therefore may be completely elevated to permit free ventilation if desired.

An outward movement of the grid from the window frame will be prevented by the 35 locking-bars 15 and 16 which normally engage in the channels 9 of the window frame, and an inward movement of the grid will be prevented by the buffer-elements 18 and 19 which engage the parting-strips 9.

40 It will be noted that the grid may be conveniently removed from the window frame whenever such removal is required, and that no mutilation or injury of woodwork of a building is necessary in the use of the device.

45 Any suitable means may be provided for maintaining the device in locked position. Numeral 20 indicates a small bracket which is secured to the lower part of the grid frame 50 (Figs. 1, 3, 5) for use in connection with the projection or buffer-element 19, the latter being provided with an aperture α (Fig. 6,) for receiving the locking-latch of a padlock 21 for securing the projection 19 to the 55 bracket 20, said bracket also being provided with an aperture (not shown) for receiving the locking-latch of the padlock.

60 In instances when the grid is used upon the window frames of hospitals or sanitariums where mental diseases are treated it is of advantage to maintain the grids in permanently locked position, and while padlocks are shown, any other suitable means may be provided for this purpose.

65 Numeral 22 (Fig. 1,) indicates a screen

preferably of wire mesh which is adapted to be secured to the outer side of the grid by any suitable means.

Numerals 23 (Fig. 6,) indicate recesses 70 formed in the outer side of the window frame 7 for receiving the frame of a storm window sash (not shown). It will be appreciated that all of the parts shown for the devices as described may be constructed of stock material, and since these parts are few and simple, manufacture of the product may be economically conducted.

75 I claim as my invention,—

In a grid for a window frame provided with channels and parting-strips, a grid having a frame adapted to be fitted into the window frame, a locking-bar rigid with one end of the grid for engaging in a channel and having a projection for engaging a parting-strip, a locking-bar mounted to have a swinging movement on the opposite end of the grid for entering a channel of the window frame and having a projection for engaging a parting-strip, and means on the last named locking-bar for preventing a swinging movement thereof.

80 In testimony whereof, I affix my signature.
JOSEPH P. CONDON.
